PREWELT LASTING MACHINE

Michael Natanson, Dorchester, Mass., assignor to
Compo Shoe Machinery Corporation, Boston,
Mass., a corporation of Delaware

Application November 23, 1943, Serial No. 511,393

20 Claims. (Cl. 12—1)

This invention relates to machines for use in the manufacture of shoes and more particularly to a machine for lasting prewelted shoe uppers and the adhesive attachment of outsoles thereto.

In the manufacture of "prewelt" shoes it is customary to last the upper to an insole and subsequently attach an outsole thereto with a suitable adhesive. This requires handling the shoe twice and if the sole is attached while the shoe is held in the lasting machine production per machine is considerably reduced.

This invention provides for the simultaneous lasting of the opposite sides of a shoe upper of a prewelted shoe and the adhesive attachment of an outsole thereto.

Objects of the invention are to reduce the time and the cost of manufacture of prewelted shoes.

Other objects of the invention will in part be obvious and will in part appear hereinafter.

For a fuller understanding of the nature and objects of the invention reference should be had to the following detailed description taken in connection with the accompanying drawings in which:

Fig. 1 is a side elevation of a shoe lasting machine embodying this invention;

Fig. 2 is a plan view looking downwardly upon the machine of Fig. 1, with a portion at one side of the machine omitted;

Fig. 3 is sectional view taken substantially along lines 3—3 of Fig. 2, but showing the shoe holding carriage advanced;

Fig. 4 is an end elevation of the machine, partly in section and having some parts broken away;

Fig. 5 is a section through the forepart of a shoe illustrating the application of the lasting wheels and the outsole pressing rollers, and

Fig. 6 is a section similar to Fig. 5 but taken through the shank portion of the shoe.

The embodiment of the invention illustrated is a lasting machine having the base 10 through which the rotary shaft 11 extends. The shaft 11 has the pinion gear 12 keyed thereto and which engages with the rack 13 which is attached to the bottom of the movable carriage 14. The hand wheel 15 is attached to the shaft 11 and serves to rotate same for advancing the carriage 14 as will be described. The carriage 14 has the upright member 16 to which is attached the toe lasting plate 17.

The movable heel supporting carriage 18 is slidably supported on and is movable with the carriage 14. It is drilled to receive the threaded shaft 19, the threads of which engage the threads of an internally threaded bore in the upright

member 16 of the carriage 14. The heel supporting carriage 18 has the upright member 20 to which is attached the heel lasting plate 21. The hand wheel 22 is attached to the shaft 19 and serves to rotate same for moving the heel lasting plate 21 forward for compensating for different sizes of shoes and also serves to last the shoe tight at the heel and toe as will be described.

The adjustable heel stop 23 is mounted on one end of the rod 24 which extends through a longitudinal bore in the upright member 20 and serves to prevent undue pressure on the stitches when the heel lasting plate 21 is moved by rotation of the hand wheel 22, into the the welt crease at the the heel end of the shoe. The screw 25 which is threaded in one side of the upright member 20 contacts the rod 24 and holds the stop 23 fixed when properly positioned.

The side lasting is provided by the wheels 26 which are tapered so as to have their edges thin at their peripheries so as to fit in the welt crease and which are rotatably mounted in the blocks 27 which are swiveled in the inner ends of the arms 28. The outer ends of the arms 28 are attached by the pivot pins 34 to the vertical shafts 29 which are mounted for rotation in the supporting brackets 30. The arms 31 are attached to the upper ends of the shafts 29 and are drilled and tapped to receive the screws 32 to the inner ends of which are attached the spring 33 which serves to urge the arms 28 and the wheels 26 inwardly towards each other and which thus provides the inward lasting pressure.

The arms 28 are pivoted for upward and downward movement about the pivot pins 34 and are urged upwardly by the compression springs 35, the inner ends of which contact the lower ends of the extensions 36 on the arms 28, and which extend in bores in the shafts 29, and the tension of which is adjustable by the screws 37 which are threaded in the shafts 29. The screws 38 which are threaded in the upper ends of the extensions 36 and which contact the shafts 29, serve as adjustable stops for limiting the upward movement of the arms 28 and the wheels 26.

The lasting wheels 26 through being rotatably mounted with the shafts 29 and through being pivoted for up and down movement are free to follow the contours of the last and to exert a constant upward and inward force for providing a tightly lasted upper.

The two sole laying pressure rolls 39 have a resilient covering 40 and are rotatably mounted on the shafts 40 which have threaded outer ends

which extend through bores in the arms 41 and are attached to the arms 41 by the nuts 42. The arms 41 are pivoted to the extensions 43 of the brackets 30 which support the shafts 29, by the pivot pins 44. The tension springs 45 have their upper ends attached to the screws 46 which are threaded into the arms 41 and have their lower ends attached to the screws 47 which are threaded into the base 10, the tension of these springs being adjustable by positioning the screws 46 and 47. The springs 45 thus urge the arms 41 and the pressure rolls 39 downwardly and provide the sole laying pressure as will be described. The set screws 48 are threaded into the arms 41 and their lower ends contact the cam bar 49 and serve to position the pressure rolls 39, at the start of the sole pressing operation.

The arms 50 have their outer ends pivoted to the inner ends of the arms 41 by the pivot pins 51 and have attached to their inner ends, the fingers 52 which serve to hold an outsole 53 clear of the cemented welt 54 of a shoe at the start of the lasting and sole pressing operation as illustrated by Fig. 1. At the conclusion of the lasting and sole pressing operation, the arms 50 with the fingers 52 are swung upwardly out of the way by the operator of the machine as illustrated by Fig. 3 so that the lasted shoe may be removed from, and another shoe may be placed in, the machine.

In operation, the operator places a last, and having assembled thereon, a conventional insole 56 and upper 55, in position with the welt pulled up over the toe lasting plate 17 and the lasting wheels 26 as illustrated by Fig. 1. He then moves the heel lasting plate 21 inwardly by rotation of the hand wheel 22 and lasts by the plates 17 and 21, the upper at the toe and the heel respectively. He then drops in a conventional filler 71 (Figs. 5 and 6) and moves the arms 50 and the separator fingers 52 downwardly and places an outsole 53 in position under the pressure rolls 39 at the toe end of the shoe and over the separator fingers 52 as illustrated by Fig. 1. Prior to this an adhesive has been applied to the lower surface of the outsole and the upper surface of the welt. He then rotates the hand wheel 15 which moves the carriage 14 forward by means of the pinion 12 and the rack 13. As the carriage and the shoe move forward the lasting wheels 26 follow in the welt crease and pull the upper upward and inward over the last. When the forward movement has started, the screws 48 clear the cam bar 49 and the pressure rolls 39 are thereby released to press the outsole against the welt. The separator fingers 52 space the outsole from the welt in advance of the pressure rolls so that the portions to which adhesive has been applied do not contact in advance of the application of the pressure rolls.

The carriage 14 is moved forward to the full extent of the shoe until the forward end of the threaded shaft 19 contacts the adjustable stop screw 58 which has been preset to bring the lasting wheels 26 and the pressure rolls 39 to the heel end of the shoe. The operator then moves the fingers 52 upwardly out of the way and reverses the direction of rotation of the hand wheel 15 bringing the carriage 14 back to its initial position against the stops 59, thus repeating the lasting and sole pressing operations. He then retracts by the hand wheel 22, the heel supporting carriage 18 which removes the heel lasting plate 21 from the shoe which is then removed.

The position of the forward end of the threaded shaft 19 is determined by the size of the shoe being lasted and the contact of the forward end of

the shaft 19 with the stop screw 58 limits the forward movement of the carriage 14, thus automatically limiting the length of travel of the carriage to the size of the shoe being lasted.

5 The sole pressure rolls 39 as illustrated by Figs. 5 and 6 are closely spaced and together are at least as wide as the outsole of any shoe to be worked upon so that pressure is exerted over the entire surface of the outsole.

10 While one embodiment of the invention has been described for the purpose of illustration, it should be understood that the invention is not limited to the exact apparatus and arrangement of apparatus illustrated as modifications thereof may be suggested by those skilled in the art without departure from the essence of the invention.

15 What is claimed is:

1. A lasting machine comprising opposed means for working opposite sides of a shoe upper over a last, a pair of substantially axially aligned, closely spaced, rolls having a combined width not substantially less than the width of an outsole for pressing said outsole against said upper, and means for moving said upper, said last and said outsole past said opposed means and said rolls.

20 2. A lasting machine comprising opposed means for working opposite sides of a shoe upper over a last, a pair of substantially axially aligned, closely spaced, rolls for pressing an outsole against said upper, means for holding said rolls a predetermined distance from said opposed means, and means for moving said upper, said last and said outsole past said opposed means and said rolls and for releasing said holding means.

25 3. A lasting machine comprising means for progressively and substantially simultaneously working opposite sides of an upper over a last, and cooperating means for progressively adhesively attaching an outsole to the marginal portions of said upper.

30 4. A lasting machine for prewelted shoes, comprising welt crease engaging means, means including said means for progressively and substantially simultaneously working opposite sides of an upper over a last, cooperating outsole pressure means, and means including said pressure means for progressively adhesively attaching an outsole to the welt of said upper.

35 5. An outsole attaching machine for a welted shoe, comprising means for simultaneously engaging the welt crease at opposite sides of the shoe, outsole pressure means, and means including said engaging means and said pressure means for progressively adhesively attaching an outsole to the welt of said shoe.

40 6. An outsole attaching machine for a prewelted shoe, comprising a pair of opposed, welt crease engaging wheels having tapered peripheries, a pair of substantially axially aligned, closely spaced, outsole pressure rolls having a combined width not substantially less than the width of the outsole of said shoe, and means including said wheels and said rolls for progressively adhesively attaching an outsole to the welt of said shoe.

45 7. A lasting machine for a prewelted shoe, comprising means including a pair of opposed, welt crease engaging wheels having tapered peripheries, a pair of substantially axially aligned, closely spaced, outsole pressure rolls having a combined width not substantially less than the width of the outsole of said shoe, and means including said wheels and said rolls for progressively working opposite sides of a shoe upper over a last and

adhesively attaching an outsole to the welt of said shoe.

8. A lasting machine comprising means for working opposite sides of a shoe upper over a last, a pair of pressure rolls arranged opposite said means for pressing an outsole against said upper, means for moving said upper, said last and said outsole past said working means and said rolls, and means for spacing said outsole from said upper in advance of its passage between said working means and said rolls.

9. A lasting machine comprising means for working opposite sides of a shoe upper over a last, a pair of pressure rolls arranged opposite said means for pressing an outsole against said upper, means for holding said rolls a predetermined distance from said working means, means for moving said upper, said last and said outsole past said working means and said rolls and for releasing said holding means, and means for spacing said outsole from said upper in advance of its passage between said working means and said rolls.

10. A lasting machine for a prewelted shoe comprising a pair of welt crease engaging wheels for working opposite sides of an upper over a last, a pair of pressure rolls arranged opposite said wheels for pressing an outsole against the welt on said upper, means for holding said rolls a predetermined distance from said wheels, and means for moving said upper, said last and said outsole past said wheels and rolls and for releasing said holding means.

11. A lasting machine for a prewelted shoe comprising a pair of welt crease engaging wheels for working opposite sides of an upper over a last, a pair of pressure rolls arranged opposite said wheels for pressing an outsole against the welt on said upper, said rolls being substantially axially aligned and closely spaced and having a combined width not substantially less than the width of said outsole, means for holding said rolls a predetermined distance from said wheels, and means for moving said upper, said last and said outsole past said wheels and rolls and for releasing said holding means.

12. A lasting machine for a prewelted shoe comprising a pair of welt crease engaging wheels for working opposite sides of an upper over a last, a pair of pressure rolls arranged opposite said wheels for pressing an outsole against the welt on said upper, said rolls being substantially axially aligned and closely spaced and having a combined width not substantially less than the width of said outsole, means for holding said rolls a predetermined distance from said wheels, means for moving said upper, said last and said outsole past said wheels and rolls and for releasing said holding means, and means for spacing said outsole from said welt in advance of its passage between said wheels and rolls.

13. A lasting machine for a prewelted shoe comprising a pair of welt crease engaging wheels for working opposite sides of an upper over a last, a pair of pressure rolls arranged opposite said wheels for pressing an outsole against the welt on said upper, said rolls being substantially axially aligned and closely spaced and having a combined width not substantially less than the width of said outsole, means for holding said rolls a predetermined distance from said wheels, means for moving said upper, said last and said outsole past said wheels and rolls and for releasing said holding means, and means for spacing said outsole from said welt in advance of its passage between said wheels and rolls.

14. A lasting machine comprising a base, a first carriage movable on said base, a toe lasting plate attached to said carriage, a second carriage

movable on said carriage, a heel lasting plate attached to said second carriage, means for positioning said second carriage on said first carriage, side lasting means attached to said base, and means for moving said first carriage past said lasting means.

15. A lasting machine comprising a base, a first carriage movable on said base, a toe lasting plate attached to said carriage, a second carriage movable on said carriage, a heel lasting plate attached to said second carriage, a heel stop attached to said second carriage adjacent said heel lasting plate, means for positioning said second carriage on said first carriage, side lasting means attached to said base, and means for moving said first carriage past said lasting means.

16. A lasting machine comprising a base, a first carriage movable on said base, a toe lasting plate attached to said carriage, a second carriage movable on said carriage, a heel lasting plate attached to said second carriage, means for positioning said second carriage on said first carriage, side lasting means attached to said base, means for moving said first carriage past said lasting means, and means including said positioning means for limiting the movement of said first carriage past said lasting means.

17. A lasting machine for a prewelt shoe, comprising a base, a first carriage movable on said base, a toe lasting plate attached to said carriage, a second carriage movable on said carriage, a heel lasting plate attached to said second carriage, means for positioning said second carriage on said first carriage, a pair of lasting wheels pivotally attached to said base for engaging the welt crease of a shoe upper supported between said toe and heel plates, a pair of outsole pressure rolls pivotally attached to said base and arranged opposite said wheels, and means for moving said first carriage past said wheels and rolls.

18. A lasting machine for a prewelt shoe, comprising a base, a first carriage movable on said base, a toe lasting plate attached to said carriage, a second carriage movable on said carriage, a heel lasting plate attached to said second carriage, means for positioning said second carriage on said first carriage, a pair of lasting wheels pivotally attached to said base for engaging the welt crease of a shoe upper supported between said toe and heel plates, a pair of outsole pressure rolls pivotally attached to said base and arranged opposite said wheels, means holding said rolls a predetermined distance from said wheels, and means for moving said first carriage past said wheels and rolls and for releasing said holding means.

19. A lasting machine for a prewelt shoe, comprising a base, a first carriage movable on said base, a toe lasting plate attached to said carriage, a second carriage movable on said carriage, a heel lasting plate attached to said second carriage, means for positioning said second carriage on said first carriage, a pair of lasting wheels pivotally attached to said base for engaging the welt crease of a shoe upper supported between said toe and heel plates, a pair of outsole pressure rolls pivotally attached to said base and arranged opposite said wheels, means for moving said first carriage past said wheels and rolls, and means for spacing an outsole from the welt of said upper in advance of its passage between said wheels and rolls.

20. A lasting machine for a prewelt shoe, comprising a base, a first carriage movable on said

base, a toe lasting plate attached to said carriage, a second carriage movable on said carriage, a heel lasting plate attached to said second carriage, means for positioning said second carriage on said first carriage, a pair of lasting wheels pivotally attached to said base for engaging the welt crease of a shoe upper supported between said toe and heel plates, a pair of outsole pressure rolls pivotally attached to said base

5 and arranged opposite said wheels, means holding said rolls a predetermined distance from said wheels, means for moving said first carriage past said wheels and rolls and for releasing said holding means, and means for spacing an outsole from the welt of said upper in advance of its passage between said wheels and rolls.

MICHAEL NATANSON.
